MACHINE FOR FORMING AND REINFORCING CUTOUTS

Lorenz F. Muther, Newton Center, and Frederick S. Glines, East Lynn, Mass.; said Glines assignor to said Muther

Application October 5, 1943, Serial No. 505,010

4 Claims. (Cl. 218—15)

1

This invention relates to a machine for forming cut-outs and applying reinforcements about the marginal portions of the cutouts.

Machines of the above type usually have two operating cycles, the first cycle being effective to punch or cut an opening in a piece of sheet material, and the second cycle being effective to apply and clench a reinforcing element, such as an eyelet, grommet or the like, about another reinforcing element, such as a washer, held against the marginal portion of the opening. When such a machine is operating considerable difficulty has been encountered when applying a grommet or eyelet about a washer or the like reinforcing element having upstanding prongs, due to the fact that the magnitude of the punching stroke, being the same as that of the clenching stroke, is apt while punching to crush or otherwise injure the pronged washer or like reinforcing element disposed about the lower punch member. If it be attempted to shorten the effective length of the punching stroke so as to avoid injury to the washer, then the magnitude of the clenching stroke, being the same, is not sufficient properly to clench the grommet about the washer.

A further difficulty encountered in such machines is the proper disposal of the punchings, it being necessary that provision be made for removing the severed material so that it will not interfere with the reinforcing operation. Although numerous attempts have been made to provide means for removing the severed material, such as mechanically operated pick-offs, air blasts and the like, all such attempts so far as we are aware have not proved generally satisfactory in that they are either more or less unreliable or embody a complicated and expensive mechanism.

The principal objects of the present invention are to overcome the aforementioned difficulties and to provide a simple, efficient and reliable machine wherein the relative magnitude of the punching and clenching strokes is, in effect, automatically varied between the two operating cycles so that both the punching and clenching devices operate properly and without danger of injuring the reinforcing elements.

A further object is to provide a simple and efficient means whereby the relative position of the operating members may be quickly changed or adjusted so as properly to operate on materials of different weight or thickness.

Further objects will be apparent from a consideration of the following description and the accompanying drawings, wherein:

Fig. 1 is a side elevation of a machine con-

2

structed in accordance with the present invention;

Fig. 2 is a front elevation of the machine shown in Fig. 1;

Fig. 3 is a section on the line 3—3 of Fig. 1, but with certain parts broken away;

Fig. 4 is a fragmentary plan view illustrating the operation of the mechanism for removing the punchings;

Fig. 5 is an enlarged vertical section through the holder for the lower punch and die;

Fig. 6 is a section through the punch members and associated dies, illustrating the manner in which a reinforcing element is clenched about the marginal portion of the cut-out formed by the punches;

Fig. 7 is a side elevation (of the side opposite that of Fig. 1) showing certain parts of the clutch mechanism; and

Fig. 8 is a section on the line 8—8 of Fig. 7.

The particular embodiment chosen for illustration is designed for punching out openings in sheet material, such as canvas, duck, etc., during the first operating cycle of the machine, and automatically applying to and clenching a reinforcing element about the marginal portion of the cut-out during the second operating cycle, it being understood that the invention is not limited to the particular type of machine herein shown since the operating instrumentalities may be used in any machine or device capable of actuating the punch members to form an opening in sheet material to which a reinforcement may be subsequently applied.

The machine here shown comprises an upstanding, hollow frame member 1 provided at its upper end with a forwardly extending head 2 and at its lower end or base portion with a laterally projecting work-supporting arm 3 vertically aligned with the head 2. A feed chute 4 and its associated hopper 5, both of which may be of conventional design and construction, are pivotally mounted on the head 2 so that the delivery end of the chute is free to swing toward and away from the outer end of arm 3, as shown in Figs. 1 and 2. Since the feed chute and associated parts are well known in the art, a further description of the construction and operation is unnecessary.

The head 2 is formed with a depending forwardly projecting arm 10 provided with an opening which slidably receives and guides a movable holder or support 11 for an operating instrumentality. The holder 11 is operated by a mechanism, hereinafter described, which is effective to

reciprocate the holder through two operating cycles, the first operating cycle causing a predetermined downward stroke of the holder 11, and the second operating cycle effecting another downward stroke of the same magnitude, and the feed chute 4 is operated to feed grommets or the like reinforcing elements R into position between the first and second operating cycles.

The operating instrumentality comprises (Fig. 6) a female punch 12 shouldered at its upper end so as to seat against the lower end of the holder 11 (Fig. 2), and having its lower end formed with a cutting edge 13 and a clenching surface 14 which provides one of a pair of cooperating clenching dies. A spindle 15 is slidably mounted within the bore of the punch 12 with its upper end projecting through an opening therein and its lower end normally extending downwardly below the cutting edge 13, as shown in Fig. 2, thereby to provide a pilot for holding a grommet R correctly positioned at the commencement of the second operating cycle, as more fully disclosed in Patent No. 2,381,818, granted August 7, 1945.

The outer end of the lower arm 3 is provided with a fixed support or holder 20 formed with a transverse slot or opening 21 and a vertically extending opening 22 which receives an operating instrumentality, comprising a cylindrical male punch 24 having an operating surface or cutting edge 25 which cooperates with that of the female punch 12 to cut a circular opening in the sheet material operated upon. An annular clenching die 26 integral with and spaced below the cutting edge 25 of the punch 24 is recessed so as to receive a washer or the like reinforcing element r and to cooperate with the clenching surface 14 of the punch 12 so as to roll the end of the grommet R over the body of the washer r, as illustrated in Fig. 6. The lower end of the punch 24 has a sliding fit within the opening 22 so that it may be reciprocated, in the manner hereinafter explained, from a retracted position to an advanced position shown by the full and broken lines, respectively, of Fig. 5.

The lower end of the punch 24 is supported on a pair of superposed slides 30 and 31 which extend through the transverse opening 21, being maintained properly centered by guide plates or walls 32 which permit the slides 30, 31 to be independently slid back and forth, as indicated by the full and broken lines of Fig. 5. The upper surface of the top slide 30 is stepped to provide a flat depressed surface 34 which adjoins a bevel 35 terminating in a flat surface 36, the bevel 35 constituting a cam element engageable with the lower end of the punch 24, as shown in Fig. 5. The under surface of the slide 30 and the upper surface of the slide 31 are planar so as to permit free sliding movement, but the under surface of slide 31 is likewise stepped to provide a flat depressed surface 38 which joins a bevel 39 terminating in a flat surface 40, the bevel 39 likewise constituting a cam element engageable with the inner end of a set screw 42 carried by the support 30. The screw 42 may be adjusted so as to vary the operating level of the slides, and a lock nut 45 is provided by means of which the set screw may be locked in adjusted position.

The ends of the lower slide 31 are formed with depending flanges 46 and 47 which not only provide stops, but also a readily accessible means by which the slide may be manually moved back and forth. One end of the upper slide 30 has a pin and slot connection 50 (Fig. 3) with one arm 51 of a bell crank lever 52 pivoted at 53 to a

bracket 54 carried by the arm 3. The lever 52 is automatically operated through appropriate connections, hereinafter described, associated with the aforementioned operating mechanism so as to actuate the slide from retracted to advance position between the first and second operating cycles, and from advance to retracted position after completion of the second operating cycle.

When the slide 30 is moved from its normal position (shown by the full lines of Fig. 5), wherein the punch 24 is supported in retracted position on the surface 34 to advanced position, i. e., toward the left (Fig. 5), the bevel or cam element 35 urges the punch upwardly to advanced position, indicated by the dot-and-dash lines of Fig. 5, thereby producing, in effect, a variation in the length or magnitude of the operating stroke of the punch 12 relative to the punch 24, it being noted that although the punch 12 travels the same distance during each operating cycle, the clenching surface 14 does not approach that of the die 26 as closely during the first operating cycle as it does during the second operating cycle. The result is therefore the same, in effect, as if the lower punch and die were held stationary and the operating stroke or travel of the holder 11 were shortened during the second operating cycle.

The particular adjustment for the set screw and lower slide is governed by the thickness of the weight of the sheet material being operated on, and for a given thickness of sheet material it is usually necessary to make but one adjustment of the set screw to hold the slides at their optimum level. The lower slide 30 may be manually operated to raise or lower the operating level, as for example, when a double thickness of the material such as a fold or hem is operated on. The upper slide 30, however, is automatically operated to hold the male punch and associated die retracted during the punching operation which takes place during the first cycle, thus avoiding an over-travel of the female punch member and consequent crushing of the washer r or injury to the prongs in case the washer is of the crown or serrated type, but during the clenching operation which takes place during the second cycle, the male punch and associated die are advanced so that the grommet R may be properly clenched about the washer r. After the completion of the clenching operation the slide 30 is again automatically operated to move the male punch and associated die back to retracted position.

Before the commencement of the clenching operation, provision is made for the removal of the punching, and to this end a brush member 60 is swivelly mounted on a clip 61 carried by the delivery end of chute 4. The brush is provided with a shank 62 about which a coil spring 64 is circumposed so as normally to hold the operative end of the brush in a retracted position, i. e., at approximately the level of and laterally offset relative to the cutting end of the male punch 24. The upper end of the shank 62 carries an arcuate extension 65 which projects inwardly so as to engage the adjacent face of the arm 10 when the feed chute swings inwardly to feeding position. The construction and arrangement of parts are such that the brush is normally held in an inoperative or retracted position (Figs. 1, 2 and 4), but when the feed chute swings inwardly, the engagement of extension 65 with the arm 10 causes the shank 62 to rotate against the action of the spring 64 and thus effects a quick sweep of the brush across the top of the male punch and the

consequent removal of a punching thereon, as indicated in Fig. 4. When the chute 4 swings back (after completion of the clenching operation) the extension 65 then disengages the arm 10 and permits the spring 64 to retract the brush to normal position.

The feed chute, punches and associated parts are operated by a mechanism which comprises a flywheel 70 connected with a two-revolution clutch 71, shown in Figs. 7 and 8, which includes gears 72 and 73 having a 1:2 ratio and respectively mounted on shafts 74 and 75 journaled in suitable openings in the frame 1. The clutch 71 is operated by a pull chain 76 (Fig. 7) which may be connected to a treadle or other convenient control member (not shown). The clutch is effective to rotate the shaft 74 through two complete revolutions, and an eccentric 80 mounted on shaft 74 and its associated connecting rod 81 operate toggle links 85 which are appropriately connected with the holder 11, as shown in Fig. 2. Thus, for each double revolution of the shaft 74, the eccentric 80 reciprocates the holder 11 twice, and the shaft 75 is rotated through one complete revolution. Since this type of mechanism is well known in the art, a further description of the construction and operation of parts is unnecessary.

The outer end of the shaft 75 is connected through bevel gears 88, 89 to a horizontally disposed shaft 90 (Fig. 1) which is suitably journaled in bearings 91, 92 integral with the frame and head, respectively. The gears 88, 89 have 1:1 ratios, and hence for each two revolutions of the shaft 74, the shaft 90 is rotated once. The outer end of the shaft 90 carries a cam 94 which operates the feed chute 4 in the manner above described, and adjacent to its opposite end the shaft 90 carries a cam 95 engageable with a roller or follower 96 mounted adjacent to the upper end of a rocker arm 98. The arm 98 is pivotally mounted at 99 on the frame 1 and its lower end is bent outwardly, as shown in Fig. 2, and terminates in an L-shaped portion having a pin and slot connection 100 (Figs. 2 and 3) with the inner end of lever 52. The rocker arm 98 is normally held in retracted position by a tension spring 102 which is secured to the upper end of the arm 98 and to the frame of the machine, as shown in Fig. 1. The design of the parts is such that during the first operating cycle the cam 94 holds the chute 4 in a retracted or inoperative position and the cam 95 remains inactive in that it permits the lever 98 to remain in retracted position under the influence of spring 102; but during the second operating cycle, the cam 94 permits the chute 4 to swing inwardly to feeding position, and at or about the same time cam 95 operates lever 98 which in turn operates slide 30 to cause the lower punch 24 to move from retracted to advanced position, as above described, and as the chute 4 swings inwardly, the brush 60 is operated to sweep across the top of the male die 24. As the shaft 90 and cams 94, 95 continue to rotate, the feed chute 4 is retracted and the lever 98 is also retracted by the spring 102, thus restoring all parts to normal position at or by the time the second operating cycle has been completed, at which time the clutch automatically disengages the shaft 74 from the flywheel 70 and locks the parts in retracted position.

Although the flywheel 70 may be driven directly at the desired speed from any suitable source, in this embodiment it is belt-connected to a pulley 110 fast to one end of a shaft 111 which extends through the base of the frame 1. The 75

opposite end of the shaft 111 carries a pulley 112 which is belt-driven by a motor (not shown) mounted on a bracket 115 bolted to the top of the frame 1, as shown in Figs. 1 and 7. By proper selection of pulley sizes, the desired speed reduction may be obtained.

In using this machine a reinforcing element, such as a plain washer *r* (Fig. 6) or a serrated washer *r'* (Fig. 5), is first manually placed on the lower-die 26, as shown in Fig. 5, and the material *S* (Fig. 6) to be operated on is then held in position on the top 25 of the male punch. The chain 76 is then depressed so as to operate clutch 71, whereupon the first operating cycle takes place during which the female punch 12 and associated parts cut an opening in the material *S*. As the punch 12 recedes, the pilot 15 temporarily holds the punching in place on the top of the male punch 24, but as the punch 12 approaches the limit of its upward movement the pilot 15 is carried upwardly to the position shown in Fig. 2, thereby leaving the punching on the top of the punch 24, and at or about the time of the completion of the first operating cycle, the cams 94 and 95 operate not only to commence swinging the chute 4 inwardly to feeding position, but also to move the male punch 24 and die 26 from retracted to advanced position. As the female punch 12 and associated parts descend for the second operating cycle, the cams continue to rotate and the following operations take place in quick succession:

(a) The brush 60 makes a quick sweep across the top of the male punch 24, clearing off the punching thereon;

(b) The pilot 15 engages a grommet *R* which is held in proper position by the chute 4 which by this time has reached the limit of its inward or feeding movement;

(c) The chute 4 recedes as the pilot 15 continues its descent, thus permitting the pilot to "pick-off" the grommet *R*;

(d) As further downward movement of the punch 12, die 24 and pilot 15 continues, the grommet *R* is carried downwardly and clenched about the washer *r*, as shown in Fig. 6;

(e) As the punch 12 starts to recede and the chute 4 completes its recession, the extension 65 disengages the arm 10 and the brush is retracted under the influence of spring 64; and

(f) Finally, the cams 94, 95 and spring 102 restore the parts to normal position preparatory to the next complete operation which takes place in the manner just described.

While we have shown and described one desirable embodiment of the invention, it is to be understood that this disclosure is for the purpose of illustration, and that various changes in shape, proportion and arrangement of parts, as well as the substitution of equivalent elements for those herein shown and described, may be made without departing from the spirit and scope of the present invention as set forth in the appended claims.

We claim:

1. In a machine of the type having a fixed support, a movable support operative to move toward and away from said fixed support and operating mechanism for moving said movable support toward and away from said fixed support, operating instrumentalities comprising male and female punches carried by the fixed and movable supports and operative to form a cutout in a piece of sheet material during the first operating cycle, cooperating dies associated

with said punches and operative during the second operating cycle to clench a reinforcing element about the marginal portions of the cutout, a slide carried by said fixed support and formed with a cam-like element engaging the lower end of the punch and associated die carried by said fixed support so as to support and selectively position said punch and associated die, and connections between said operating mechanism and slide effective to move the last-mentioned punch and associated die from a retracted position to an advanced position between the completion of the first and second operating cycles and then back to retracted position after the completion of the second operating cycle.

2. In a machine of the type having a fixed support, a movable support operative to move toward and away from said fixed support, and operating mechanism for moving said movable support toward and away from said fixed support, operating instrumentalities comprising male and female punches carried by the fixed and movable supports and operative to form a cutout in a piece of sheet material during the first operating cycle, cooperating dies associated with said punches and operative during the second operating cycle to clench a reinforcing element about the marginal portions of the cutout, the punch and associated die carried by said fixed support being slidably mounted therein so as to move toward and away from the punch carried by said movable support, and means carried by said fixed support for selectively varying the position of the punch and associated die carried thereby, said means comprising cam-like members movable relative to each other and to said support, and connections between one of said cam-like members and said operating mechanism effective to operate the cam-like member so as to move the last-mentioned punch and associated die from a retracted position to an advanced position between the completion of the first and second operating cycles and then back to retracted position after completion of the second operating cycle, the other of said cam-like members being manually movable independently and operative to effect a further variation in the position of said last-mentioned punch and associated die.

3. In a machine of the type having a fixed support, a movable support operative to move toward and away from said fixed supporting and operating mechanism for moving said movable support toward and away from said fixed support, operating instrumentalities comprising male and female punches carried by the fixed and movable supports and operative to form a cutout in a piece of sheet material during the first operating cycle, cooperating dies associated with said punches and operative during the second operating cycle to clench a reinforcing element about the marginal portions of the cut-out, means associated with said fixed support for selectively

varying the position of the punch and associated die carried thereby, said means comprising a pair of superposed cam-like members movable relative to each other and to said support, the inner cam-like members being engageable with the punch and associated die carried by said support and the outer cam-like member being engageable with the inner cam-like member, and connections between one of said cam-like members and said operating mechanism effective to operate the cam-like member so as to move the last-mentioned punch and associated die from a retracted position to an advanced position between the completion of the first and second operating cycles and then back to retracted position after completion of the second operating cycle, the other of said cam-like members being manually movable independently and operative to effect a further variation in the position of said last-mentioned punch and associated die.

4. In a machine of the type having a fixed support, a movable support operative to move toward and away from said fixed support and operating mechanism for moving said movable support toward and away from said fixed support, operating instrumentalities comprising male and female punches carried by the fixed and movable supports and operative to form a cutout in a piece of sheet material during the first operating cycle, cooperating dies associated with said punches and operative during the second operating cycle to clench a reinforcing element about the marginal portions of the cutout, a slide carried by said fixed support and formed with a cam-like element engageable with the lower end of the punch and associated die carried by said fixed support so as to support and selectively position said punch and associated die in either a retracted position or an advanced position, and means for moving said slide from one position to another so as to effect the aforesaid variation in the position of the punch and associated die.
